Attorney

UNITED STATES PATENT OFFICE.

GLENN R. HOFFMAN, OF SPRINGFIELD, ILLINOIS, ASSIGNOR TO HOFFMAN MANUFACTURING COMPANY, OF SPRINGFIELD, ILLINOIS, A CORPORATION OF ILLINOIS.

TRANSMISSION BAND.

Application filed March 5, 1923. Serial No. 622,911.

To all whom it may concern:

Be it known that I, GLENN R. HOFFMAN, a citizen of the United States, residing at Springfield, in the county of Sangamon and State of Illinois, have invented certain new and useful Improvements in Transmission Bands; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to brake-bands of the type employed in automobile transmissions, more especially, transmissions of the Ford car. It has for its object to provide improved features of construction in one of the ears of the transmission band whereby the ear may be readily separated from the band to facilitate the removal of the band from the band-drum and whereby stability of attachment of the ear to the band will be effected. To the accomplishment of the foregoing and such other objects as may hereinafter appear the invention consists in the features hereinafter particularly described and then sought to be clearly defined by the claims, reference being had to the accompanying drawing forming a part hereof and in which—

Figure 1 is a perspective view of the detachable ear of a transmission band, removed from the band;

Figure 2 a top plan view of the same on a large scale;

Figure 3 a side view, with a portion of the band broken away, showing both ears applied to the band.

In the drawing the numerals 1 and 2 designate the ears of a transmission band comprising a metal strap or band 3 with a lining 4 of woven fabric, or other suitable material. The ear 2 is designed to be permanently attached to the band by rivets or otherwise, and the ear 1 is designed to be removably attached to the band so as to be separated from the band when required to facilitate placing the band in position around the transmission drum and also removing it from the drum for repairs or other purposes, the separable attachment of

one ear making possible the easier and more expeditious placement and replacement of the transmission band without removal of other parts between which and the transmission band there would be interference if both ears of the band were permanently attached to the band, as for instance in the transmission of a car of the Ford type. To facilitate the easy placing and removal of the detachable ear and to securely hold it in place in its attachment to the band, the ear 2 is formed in its shank portion 5 with slots 6 enlarged at one end to receive headed studs 7 attached to the metal band 3 and also formed on its under face adjacent to the notched end of the ear with a slot or recess 8 having front and rear walls as shown and designed to receive a shoulder or stud 9 projecting from the face of the band 3 so as to prevent the ear from slipping lengthwise when in locked attachment to the band, 70 To place the ear in position the heads of the studs 7 are inserted through the enlarged ends of the slots and the ear moved in the direction of the adjacent end of the band so as to bring the studs 7 into the narrower portions of the slots with their heads bearing against the outer face of the ear shank. As the ear is slid to the position mentioned the stud or projection 9 will snap into the recess 8 and thus the ear will be locked to the metal band and held against longitudinal movement. When the ear is to be detached from the band the latter is pressed inward, away from the ear, so as to withdraw the stud 9 from the recess 8 and the ear then slid to bring the heads of the studs 7 into the enlarged ends of the slots 6, when the ear can be lifted from the band. If desired the end of the band 3 may be bent upwardly to form a flange 10 to bear against the end of the ear as shown in Figure 3 and thus afford an additional bearing for the end of the ear and which also will serve as a bearing for a tool that may be used to press the metal band 100 inward so as to disengage the stud 9 from its socket or recess 8.

The features specified constitute a simple and very efficient construction permitting the easy placement, removal and replacement of the ear, and securely holds the ear in position without danger of accidental displacement.

Having described my invention and set forth its merits what I claim is:

1. A transmission band provided with a removable ear formed with a slot having an enlarged portion and with a socket in its under face having front and rear walls, and a band provided with a headed stud to fit in the slot of the ear and with a stud positioned to fit in the socket of the ear and bear against the front and rear walls thereof to prevent longitudinal movement and with an upturned flange to bear against the end of the ear.
2. A transmission band provided with a removable ear formed with a slot having an enlarged portion and with a socket in

its under face having front and rear walls, and a band provided with a headed stud to fit in the slot of the ear and a stud positioned to fit in the socket of the ear and bear against the front and rear walls thereof to prevent longitudinal movement and with an upturned flange to bear against the end of the ear. ²⁰

In testimony whereof I affix my signature in presence of two witnesses.

GLENN R. HOFFMAN.
